PATRICK H. KANE, OF BUFFALO, NEW YORK.

CONCRETE-REINFORCING BAR.

1,100,742.

Specification of Letters Patent. Patented June 23, 1914.

Application filed January 15, 1912. Serial No. 371,338.

To all whom it may concern:

Be it known that I, PATRICK H. KANE, a citizen of the United States, residing at Buffalo, in the county of Erie and State of New York, have invented new and useful Improvements in Concrete-Reinforcing Bars, of which the following is a specification.

This invention relates to the bars employed for reinforcing concrete structures, such as columns and beams.

One object of my invention is the provision of a reinforcing bar of this character which shall possess great strength in comparison with its weight, which can be bent or wound, without buckling, into spiral and other forms required in producing columns, girders and other structural members and which can be cheaply produced by rolling.

20 A further object is to so construct the bar that the concrete in which it is embedded is firmly interlocked therewith, in order to form a strong and reliable bond between the parts of the structure.

25 In the accompanying drawings: Figure 1 is a fragmentary perspective view of a bar embodying the invention. Fig. 2 is a transverse section of a concrete column or beam reinforced by such bars. Fig. 3 is a section showing a modified form of the bar. Figs. 4, 5 and 6 are fragmentary side elevations of suitable rolls for producing the bars.

30 Similar numerals of reference indicate corresponding parts throughout the several views.

1 indicates a concrete structure, such for example as a column or a beam, which is reinforced by a number of the improved bars 2. As shown in Fig. 1, the bars extend 40 lengthwise of the concrete structure and are suitably spaced or distributed and employed in such numbers as may be required by the size of the structure and the weight to be carried by it.

45 Referring to the construction shown in Figs. 1 and 2, each of these bars consists of a core or body 3 and four or more longitudinal webs 4 extending outwardly from the body in different directions and provided 50 with laterally-projecting anchoring heads, flanges or enlargements 5 which extend from both sides of each web.

55 In its preferred form, the reinforcing bar is substantially cruci-form in cross section, as shown, and each of its webs is provided at its outer edge with a head or enlargement 6

projecting laterally beyond both sides thereof and extending continuously from end to end of the web similar to the head or ball of a railway rail. This construction produces great strength with comparative lightness and at the same time presents extensive anchoring members or projections for the surrounding concrete. It will be observed 60 that adjacent webs of the bar with their laterally-projecting heads or flanges form an undercut or dovetailed space which receives the concrete, firmly and reliably interlocking it with the webs or vice versa. The 70 concrete is thus held intact and prevented from falling away from the reinforcing bars even in the event of its becoming cracked or loosened. While reinforcing the concrete, the bars in turn remain fully incased by the concrete, producing a thoroughly fire-proof construction. As the heads of the several webs are all integral therewith, the bar can be doubled without buckling to form beam or girder units, or wound in spiral or other 80 form around a group of similar longitudinal bars to form columns.

In order to further anchor the reinforcing bars in the concrete structure they may be provided with projecting ribs or corrugations 7 of any suitable form and with anchoring grooves 8 alternating with said ribs; or if desired, either the ribs or the grooves may alone be employed. These ribs or grooves also effectually resist longitudinal 90 slippage or displacement of the bars in the concrete.

The invention is not confined to bars of cruciform cross section but is applicable to various other shapes and forms capable of 95 being conveniently rolled.

The bar shown in Figs. 1 and 2 when rolled according to the ordinary method is formed at the junction of its webs with angular longitudinal ribs 10, but if desired it 100 may be rolled without such ribs, as shown in Fig. 3. The bar with its webs and heads is rolled solid from a single blank of metal. Suitable rolls for this purpose are shown in Figs. 4, 5 and 6.

105 11 and 12 indicate a pair of roughing-rolls provided in their meeting faces with coöperating deep and shallow grooves 13 and 14 of the proper shape to roll the blank 15' to a substantially cruciform cross section, as 110 shown in Fig. 4.

15 and 16 indicate a pair of finishing rolls

provided with deep and shallow grooves 17 and 18 corresponding to the grooves 13 and 14, for forming the four webs of the bar and also having additional annular grooves 19 and 20 for forming two opposite heads 6 of the bar. The shallow grooves 18 are provided with transverse grooves 21 and ribs or projections 22 to form the anchoring ribs or corrugations 7 and anchoring grooves 8 10 of the reinforcing bar.

In rolling the bar, after passing the blank through the first pair of rolls 11 and 12, it is passed through the finishing rolls 15 and 16, whereby two of its webs 4 are headed 15 and corrugated, as shown in Fig. 5. The bar is then given a quarter-turn and again passed through said finishing rolls, thereby heading and corrugating the remaining two webs and completing the bar, as shown in 20 Fig. 6. The solid rolled bar so produced, while affording the advantages of lightness, great strength and a strong and reliable bond with the concrete structure, can be rolled at relatively small cost in a variety 25 of sizes, including bars as small as a quarter of an inch in diameter. Such small bars are useful as binders by bending or winding them around a group or cluster of larger bars, in a manner well known in this art.

I claim as my invention:

1. A solid, rolled reinforcing bar for concrete structures, comprising a body-portion and four or more longitudinal webs extending therefrom in different directions and each provided at its outer edge with a head 35 extending beyond both sides of the web, forming undercut concrete-receiving spaces between the adjacent webs, said body-portion, webs and heads being all rolled integral from a single blank of metal. 40

2. A solid, rolled reinforcing bar for concrete structures, comprising a body portion and four or more longitudinal webs extending therefrom in different directions, said webs being provided on their sides with 45 anchoring means and each web having at its outer edge a head which extends beyond both sides thereof, forming undercut concrete-receiving spaces between the adjacent webs, said body portion, webs, heads and anchoring means being all rolled integral from a single blank of metal. 50

Witness my hand this 11th day of January, 1912.

PATRICK H. KANE.
